UNITED STATES PATENT OFFICE.

ALBERT F. HILL, OF CHICAGO, ILLINOIS.

IMPROVEMENT IN TRACE-CARRIERS.

Specification forming part of Letters Patent No. **222,046**, dated November 25, 1879; application filed April 15, 1879.

To all whom it may concern:

Be it known that I, ALBERT F. HILL, of Chicago, in the county of Cook, and in the State of Illinois, have invented certain new and useful Improvements in Trace-Carriers; and I do hereby declare that the following is a full, clear, and exact description thereof, reference being had to the accompanying drawings, and to the letters of reference marked thereon, making a part of this specification.

The nature of my invention consists in the construction and arrangement of a trace-carrier, as will be hereinafter more fully set forth.

In order to enable others skilled in the art to which my invention appertains to make and use the same, I will now proceed to describe its construction and operation, referring to the annexed drawings, in which—

Figure 1 is a plan view of my trace-carrier. Fig. 2 is a cross-section of the same.

A represents a rectangular metallic frame, of any suitable dimensions, having the hip-straps B B, back-strap C, and crupper-strap D connected thereto.

In the frame A are two parallel cross-bars, a a, which are connected by pins b b, and upon each of these pins is pivoted a hook, F. The end of this hook has the opening I, large enough

to allow only the smallest part of the cockeye to enter—namely, near the neck of the cockeye. G represents the trace with the cockeye H.

When the traces are unhitched the cockeyes are inserted in the hooks F, and as they hang down in natural shape the larger part of the cockeye turns into the hook, which prevents them from coming out. They can only be taken out by turning the cockeyes until their smallest part near the neck gets to the entrance of the hooks.

Having thus fully described my invention, what I claim as new, and desire to secure by Letters Patent, is—

The combination of the frame A, having cross-bars a a, and pins b b, with the pivoted hooks F F, having narrow throats I I, constructed and arranged to allow the neck only of the cockeye on the end of the trace to enter, substantially as and for the purposes herein set forth.

In testimony that I claim the foregoing I have hereunto set my hand this 7th day of April, 1879.

ALBERT F. HILL.
